CLAIM

The ornamental design for the tool storage bag divider, as shown and described.

DESCRIPTION

FIG. 1 is a perspective view of a tool storage bag divider; FIG. 2 is a rear perspective view of the tool storage bag divider of FIG. 1;

FIG. 3 is a cross section view through a first portion of a tool storage bag to show a front view of the tool storage bag divider of FIG. 1;

FIG. 4 is a cross section view through a second portion of a tool storage bag to show a rear view of the tool storage bag divider of FIG. 2; and,

FIG. 5 is a top view of the tool storage bag divider showing the divider of FIG. 1 and FIG. 2 from above.

The broken lines of the tool storage bag in FIGS. 1-5 are illustrative of portions of the tool storage bag divider that form no part of the claimed design.
